No. 12,377

Aug. 2, 1881

UNITED STATES PATENT OFFICE.

RODOLPHE CHRISTESEN, OF NEW BRITAIN, CONNECTICUT, ASSIGNOR TO THE RUSSELL & ERWIN MANUFACTURING COMPANY, OF SAME PLACE.

DESIGN FOR A DROP-LETTER PLATE AND BELL-LEVER.

SPECIFICATION forming part of Design No. 12,377, dated August 2, 1881.

Application filed May 25, 1881. Term of patent 7 years.

To all whom it may concern:

Be it known that I, RODOLPHE CHRISTESEN, a citizen of the United States, residing at New Britain, in the county of Hartford and State 5 of Connecticut, have invented and produced a new and original Design for a Drop-Letter Plate and Bell-Lever, of which the following is a specification, reference being had to the accompanying engraving, forming part there- 10 of, which represents the same in perspective.

The lever A and its handle B, so much of the plate C as is above the lower end of the lever, and the lower end of the plate are of the same design as the bell-lever and plate 15 shown and described in my application No. 34,245—design for bell-lever and its plate—filed May 25, 1881, and the major portion of the drop-letter plate, or part of the plate below the bell-lever, is shown and described in my 20 application No. 34,244, for drop-letter plate, filed May 25, 1881, and for that reason need not be herein fully described.

In my design for drop-letter plate and bell-lever the parts are arranged differently and 25 some new features added. The border is single instead of double at the vertical sides, and the wings *a a* upon either side of the let-

ter-mortise project a little beyond the sides, as shown. These wings are also located above the center of the letter-mortise. Just above 30 the letter-mortise is the central ornament, *b*, consisting of a rectangular panel containing raised ornaments, and surrounded by ornamental raised bars disposed as shown. Above and below the side wings, and upon the two 35 sides of the letter-mortise and central figure, *b*, there are four small and narrow panels, containing ornamental work in relief, as shown.

I claim—

The design for a drop-letter plate and bell- 40 lever herein shown and described, the same consisting of the plate C, having the single border and the projecting side wings, *a a*, with the upper end of said plate ornamented by the vase and flowering plant, the lower end by the 45 rosettes and leaflets, the middle portion by the central ornament, *b*, and the remaining panels with inclosed ornaments, and the lever A and handle B projecting from said plate.

RODOLPHE CHRISTESEN.
